UNITED STATES PATENT OFFICE.

JOHN B. DAVIS, OF DAYTON, OHIO, ASSIGNOR TO THE NATIONAL OIL PUMP & TANK CO., OF DAYTON, OHIO, A CORPORATION OF OHIO.

SELF-MEASURING OIL-PUMP.

No. 874,574.

Specification of Letters Patent.

Patented Dec. 24, 1907.

Application filed August 3, 1907. Serial No. 386,885.

To all whom it may concern:

- Be it known that I, JOHN B. DAVIS, citizen of the United States, residing at Dayton, in the county of Montgomery and State of Ohio, have invented certain new and useful Improvements in Self-Measuring Oil-Pumps; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.
- 15 This invention relates to improvements in self-measuring oil pumps, and more specifically to the means for actuating the pistons, and to means for regulating the throw of the piston and plunger rods.
- 20 The object of the invention is to provide an efficient means for reciprocating the pistons of the pump, such as two chain connections between the plunger rods, one chain being the elevating chain and the other the 25 pulling-down chain.

Another object of the invention is to provide an adjustable stop common to both plunger rods and by means of which the discharge from the two cylinders is regulated.

30 Preceding a more detailed description of the invention, reference is made to the accompanying drawings, of which—

Figure 1, is an enlarged elevation partly in section of a double cylinder pump constructed 35 in accordance with said invention. Fig. 2, is a sectional elevation of the upper portion of the pump on the line 2—2 of Fig. 3. Fig. 3, is a sectional elevation on the line 3 3 of Fig. 2. Fig. 4, is a sectional view on the line 4 4 40 of Fig. 2. Fig. 5, is a section on the line 5 5 of Fig. 3.

In a detail description of the invention, similar reference characters indicate corresponding parts.

45 The two cylinders 1 1 of the pump are mounted on a hollow base 2 and are supplied through a pipe 4 within the base, said pipe being connected to a suction pipe 3 leading to the source of supply, and the pipe 4 50 having seated in the ends lying within the cylinders, suction valves 5. The pistons 6 are connected to plunger rods 7 extending through a sub-base 13 which is mounted upon the upper ends of the cylinders. Connected to the ends of the plunger rods 7 is a

lifting chain 8 through which the plunger rods are elevated. This chain passes over two sprocket wheels 9 mounted in the head 10 at the top of the machine. The head 10 is supported on the sub-base 13 by means of 60 legs 7 that extend down and are bolted to said sub-base. The plunger rods 7 pass through stuffing boxes 11 located at the sub-base and upon the upper portions of the plunger rods there are secured by means of 65 set screws 12 adjustable pieces 10' which may be moved to suitable points on the plunger rods to regulate their stroke and there secured. Connected to these adjustable pieces 10' is a draw chain 8' by which 70 the plunger rods are drawn down. This chain passes around a sprocket wheel 14 mounted upon a shaft 12' within a housing 15 resting upon the sub-base 13. The sub-base 13 is recessed as at 16 below the sprocket 75 wheel 14 to permit the chain to pass around said sprocket wheel and the shaft 12' of said sprocket wheel is journaled in the sides of the housing 15. Secured to the ends of the shafts 9' upon which the upper sprocket 80 wheels 9 are mounted, are intermeshing gear wheels 17 and 18. The shaft of the smaller of these gear wheels is turned by a crank handle 19 and thus the chain wheels 9 9 are actuated to drive the chains 8 and 8', chain 85 8 to elevate a plunger rod, and chain 8' to pull down the plunger rod previously elevated. The spur wheel 18 is fixed to shaft 9' while the crank handle 19 and the gear 17 are connected together and are loose upon 90 their shaft.

In the operation of the machine, the crank handle 19 is turned to elevate one of the pistons through the chain 8 and to pull down the other piston through the chain 8' as before indicated. The pistons 6 are of the well-known valve type, and the descending piston elevates the oil into the chamber 20 in the sub-base 13, from whence it is discharged through the outlet pipe 21. It will be understood that the pistons each draw into their respective cylinders the oil through the valve 5 when ascending, and that when descending, the oil previously drawn in to one or the other cylinder is forced above the piston to 100 105 subsequently drawn into the chamber 20 and forced out through the discharge pipe 21.

The adjustment by which the throw of the pistons is regulated, and the proper and accurate measures are taken from the cylinders, 110

is obtained through means of a center rod 22 which is mounted on the sprocket housing 15 and has its upper end screw-threaded for the necessary length and engaged by a center piece 23 secured to the head 10 of the framework, so that the said central rod is properly supported at its top and bottom. 24 is an adjustable collar on said center rod; this collar is screwed to the proper point on the central rod 22 and is then made tight by means of a set screw 25. The flange on said collar is in the path of the inner ends of the adjustable pieces 10', and the plunger rods are limited in their movements by engaging this stop collar; and during which movement the contents of the cylinders are accurately discharged. To discharge less than the full contents of each cylinder, say for example, a quart, or a pint, other stops 27 and 28 are employed; these stops are fixed in the proper positions for the extended portions 27' and 28' to be engaged by the inner extended portions of the adjustable pieces 10'. The lower end of the central rod 22 has fixed to it an indicating device 26 which is moved to a point on the sub-base 13 to indicate "1 Qt" or "1 Pt". When the said pointer 26 is moved to one of these positions, the stops 27 or 28 are moved to a corresponding point or in alinement with the inner end of one of the adjustable pieces 10'.

I claim:

1. In a self-measuring oil pump, the combination of two cylinders, pistons with plunger rods therein, adjustable pieces on the upper ends of said plunger rods, a pulling-down chain connected to the inner ends of said adjustable pieces, a sub-base, a sprocket wheel mounted in the sub-base and around which said pulling-down chain passes, a lifting chain, the ends of which are attached to the upper ends of the plunger rods, sprocket wheels mounted in the top of the machine and over which said last-named chain passes,

a crank handle, and gearing operated by said crank handle and by which said sprocket wheels are rotated to reciprocate the plunger rods and therewith the pistons in the cylinders through the pull and lift chains as specified.

50

2. In a self-measuring oil pump, a supporting frame having a head, two pump cylinders, two pistons and plunger rods, a sub-base above the cylinders having a sprocket housing thereon, an adjustable piece secured to the upper end of each plunger rod, a pulling-down chain having its ends secured to said adjustable pieces, a sprocket wheel mounted in the sprocket housing on the sub-base and around which said pulling-down chain passes, a lifting chain secured to the upper ends of the plunger rods, sprocket wheels mounted in the head of the machine and over which said lifting chain passes, intermeshing gear wheels on the shafts of said sprocket wheels, and a crank handle to initially drive one of said gear wheels to transmit the lifting and pulling power to said chains.

60

3. In a self-measuring oil pump, two pump cylinders, a piston and plunger rod in each pump cylinder, a lifting chain having its ends attached to the upper ends of the plunger rods, adjustable pieces carried on the upper ends of the plunger rods, a pulling-down chain having its ends attached to the adjustable pieces, said pulling-down chain extending downwardly from the ends of the plunger rods, and means to actuate the lifting chain to elevate a plunger rod, and the pulling-down chain therewith, and whereby the other plunger rod is lowered.

75

In testimony whereof I affix my signature, in presence of two witnesses.

JOHN B. DAVIS.
